(57) **CLAIM**

The ornamental design for a hair extension with grooved tip.

DESCRIPTION

FIG. 1 is a top plan view of a hair extension with grooved tip showing my design;

FIG. 2 is a bottom plan view thereof;

FIG. 3 is a right side-elevation view thereof;

FIG. 4 is a left side-elevation view thereof;

FIG. 5 is a front elevation view thereof;

FIG. 6 is a rear elevation view thereof; and

FIG. 7 is a perspective view thereof; and,

FIG. 8 is a perspective view thereof with the entire extension hair shown.

In FIGS. 1-7, for clarity of illustrating the grooved tip, strands of extension hair are partially illustrated.

The broken lines in FIGS. 4 and 7 illustrate holes and form no part of the claimed design.
